(57) **CLAIM**

The ornamental design for a container holding device, as shown and described.

DESCRIPTION

FIG. 1 is a perspective view container holding device in an expanded position having a container located on the container holding device;

FIG. 2 is a perspective view of the container holding device in a compressed position;

FIG. 3 is a perspective view of the container holding device in a expanded position;

FIG. 4 is a front elevational view thereof;

FIG. 5 is a rear elevational view thereof;

FIG. 6 is a right side elevational view thereof;

FIG. 7 is a left side elevational view thereof;

FIG. 8 is a top elevational view thereof; and,

FIG. 9 is a bottom elevational view thereof.

The broken lines in the drawings illustrate the portions of the container holding device and environmental structure that form no part of the claimed design.
